UNITED STATES PATENT OFFICE.

ANTONI JAROCH, OF YORKVILLE, OHIO.

WINDOW SCREEN.

Application filed July 19, 1927. Serial No. 206,995.

This invention relates to window screens. The ordinary collapsible window screen is very well known and this screen is very widely used. However, the use of this type 5 of screen presents many objections and among these may be mentioned that it is impossible under present conditions to prevent such a screen from being removed from the outside of the house since even if the 10 window sash itself is provided with some means by which it cannot be raised the screen may be collapsed and simply moved outward from beneath the sash.

One important object of the present 15 invention is to so improve the construction of such window screens that once they are inserted between the sides of the window frame and adjusted thereto they cannot be collapsed from the outside but can only be 20 released for collapsing movement from the inside. Thus such screens may be prevented from surreptitious removal.

A further objection to the use of such 25 screens is that ordinary windows are not provided with means for locking them in adjustably open position so that when such screens are used the window may still be raised and even if the screen is provided with means to prevent its collapse from the 30 exterior of the building a person seeking unlawful entrance may raise the window, reach inside and release the means employed to prevent collapse.

A second important object of the present 35 invention is to provide in combination with a screen arranged so that it cannot be collapsed from the exterior of means attachable to the screen and sash and preventing opening of the sash beyond that necessary merely 40 to allow the screen proper room between the end of the window frame and the sash.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is an inside view of a window frame showing the improved screen and sash holding means in position.

Figure 2 is a section on the line 2-2 of Figure 1.

Figure 3 is a detail view in elevation showing the means for holding the screen members expanded.

Figure 4 is a bottom plan view of the parts 60 shown in Figure 3.

Figure 5 is an enlarged detail side elevation of the sash locking means.

Figure 6 is an enlarged detail section on the line 6-6 of Figure 5.

In illustrating the invention it has been shown in Figures 1 and 2 as applied to a window whereof the frame sides are indicated at 10, the upper end at 11 and the lower end or sill at 12. This window has 70 its sides provided with the usual beads 13 and between these beads slide the upper sash 14 and the lower sash 15. The screen has been here shown positioned beneath the lower sash 15 and consists of the usual pair 75 of sections 16 and 17 telescopically connected so that they may be fitted to any width of window within the range of their telescoping movement. To the side frame member 80 of one of these sections are secured brackets 18 by means of which a U-shaped frame having horizontal legs 19 is carried on this section, here shown as the section 17. These legs 19 pass beneath brackets 20 secured to the top and bottom frame members of the 85 other section 16 and the brackets 20 are provided with openings for the reception of latch pins 21 which also pass through one or the other of a series of spaced openings 22 in the parts 19. By this means when the 90 screen is inserted and spread so that its sides engage between a pair of the beads 13 the pin 21 may be dropped through the openings and the screen cannot be collapsed for removal until these pins are withdrawn. 95

It is intended that the brackets and pins shall be positioned on the inner side of the screen. Also on one of the horizontal frame members of a screen section is fixed a vertical socket 23 wherein fits the lower end 100 24 of a bar 25 formed by bending a sheet of metal into a T-shaped tube or guide. The upper end of this bar 25 is provided with a laterally and downwardly extending hook 26 which hooks over the upper member of the sash 15, the length of the bar 25 being substantially the height of the sash so that when the sash is closed down and the hook 26 engaging on top thereof the end 24 will enter the socket 23. Slidable in this 110 bar 25 is an extension bar 27 of T-shape in cross section and having its web projecting

from the bar 25 as clearly shown in Figures 5 and 6. The edge of this web is provided with spaced notches 28 engageable by a pivoted finger actuated latch 29 carried by the bar 25. The lower end of the bar 27 is also provided with a finger piece 30 for assisting in raising the same while the upper end is provided with a bracket 31 engageable beneath the top member of the upper sash 14. Thus with this bar in position the lower sash can neither be raised nor lowered because the hook prevents its being raised while the screen prevents its being lowered. Also the upper sash cannot be lowered because the bracket 31 prevents this. Thus with this screen and the telescopic sash holding bar in position access cannot be had to the interior of the building without the destruction of the screen or cutting out or breaking the glass of the window.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

1. In a structure of the character de-

scribed, wherein a window frame has a sliding sash therein, and a screen adapted to fit in said frame between the sash and an end of said frame; a bar consisting of a pair of telescopically connected sections, a hook member on one of the sections adapted to engage over the end of the sash remote from the screen, said screen having a socket to receive the end of the hook, means on the other section of said bar engaging the frame end remote from the screen, and a latch adapted to hook the bar sections releasably in adjusted position.

2. In a structure of the character described wherein a window frame has a sliding sash therein, and a screen adapted to fit in said frame between the sash and an end of the frame; a bar consisting of a pair of telescopically connected sections, a hook member on one of the sections adapted to engage over the end of the sash remote from the screen, said screen having a socket to receive the end of the hook, means on the other section of said bar engaging the frame end remote from the screen, one of said sections being provided with a series of notches spaced therealong, and a finger operated latch pivoted to the other bar section for selective latching engagement in said notches.

In testimony whereof I affix my signature.

ANTONI JAROCH.
